UNITED STATES PATENT OFFICE

2,668,949

TRANSMITTING TUBE SOCKET

Rudolf Leopold, Oakland, and Joseph R. Casamento, West New York, N. J., assignors to Allen B. Du Mont Laboratories, Inc., Passaic, N. J., a corporation of Delaware

Application December 31, 1949, Serial No. 136,306

1 Claim. (Cl. 339—194)

1

This invention relates to sockets for electron discharge devices and particularly to the connecting members for the electrode connecting pins extending from the glass base of the discharge device.

It is well known that in electronic apparatus designed to operate at frequencies of the order of one-hundred megacycles or more, the connections between components in the circuits should be as short as possible. This is particularly true of components connected to the amplifying tubes, and one means by which these short connections to the tubes may be effected is by eliminating the tube socket, which is standard in most low frequency tubes, and connecting directly to the pins at a point near where they are sealed to the tube. There is no difficulty in making these connections to low power tubes where the currents are comparatively small, but for larger power transmitting tubes, such as for instance the present day type 4X-500A, it is necessary that the connecting devices be both short and flexible in order that strains set up by the heating action of the large currents will not crack the glass seal of the tube. This is particularly true of the pins to which the filament is connected. Another important consideration in these transmitting tubes is that the socket must support a considerable weight and must therefore be of rigid construction.

It is one object of this invention to provide an improved tube socket.

The second object is to provide an improved socket for high frequency transmitting type tubes.

A third object is to provide a rigid socket having adjustable pin connectors.

Other objects will be apparent to those skilled in the art after studying the specification together with the drawings, in which:

Figure 1 is a perspective view of a transmitting tube and its socket;

Figure 2 is a bottom view of the socket showing an arrangement for two tubes; and

Figure 3 is an enlarged side view, partially in cross section, of a pin connector as used in the sockets of Figures 1 and 2.

In Figure 1 a transmitting tube 11 is shown in position to be inserted into its socket. The pins 12 and 13 of the tube 11 fit into the socket connections 14 and 16 respectively and the metal ring 17 on the tube 11 is held by a spring connector ring 18. This spring connector ring 18 is securely attached as by soldering to a plate 19 which is separated from a second plate 21 by a sheet of insulating material 22 such as mica.

2

The two plates 19 and 21 are held together by a number of insulated bolts 23.

Figure 2 shows the socket from the under side. Provisions for two tubes are made in this socket, since these tubes may be operated in a push-pull circuit although a two-tube socket is not necessary in order to carry out this invention. The two pairs of connectors 14 and 16 are shown as filament connectors and are located in plates 24 and 26 having terminal posts 27 and 28 respectively to which the connections from a filament transformer (not shown) may be made. The plates 24 and 26 are separated from the plate 21 by insulating sheets 29 and 31 which are similar to the insulating sheet 22 of Figure 1.

In Figure 3 a connector (14 or 16) is shown greatly enlarged. The pin 14 consists of a tubular member 34 having an end flange 36 and another flange 37, longitudinally spaced a short distance therefrom. This spacing is not critical but is slightly greater than the thickness of the plate 24. The tubular member 34 is slotted with a plurality of longitudinal slots forming a plurality of longitudinal resilient fingers beginning at a point below the second flange 37 and continuing to the lower end, i. e., that end not flanged.

As may be seen in Figure 3, the outer diameter of the body portion of the tubular member 34 is less than the diameter of the opening 42 in the plate 24. This permits the connector to move laterally with respect to the plate and compensate for structural or manufacturing variations in the tube pin location and also for the difference in the coefficient of expansion of the metal plates 24 and 26 and the glass base of the tube 11 which would set up strains that might easily crack the tube if the pins were held in a fixed position.

The inner rim of said tubular member 34 at the end adjacent the flange 36 is preferably beveled to facilitate the entry of the pin 12. The interior thereof is taper reamed or bored so that the inner diameter is larger than the external diameter of the pin 12 adjacent the beveled end, but is smaller than the diameter of the pin 12 at the other end of the tubular member. Thus the pin 12 may be easily inserted into the beveled end, encountering an increasing amount of frictional resistance, so that it is held by friction and the spring tension of the resilient fingers, making for better electrical contact.

In assembly, the slotted end of the tubular member 34 is inserted into an opening 42 provided therefor in the plate 24 and since the flange 37 has a diameter smaller than the di-

ameter of the opening it also passes therethrough. The flange 36, being larger, abuts against the plate 24 so that the connecting member 14 is supported or suspended therefrom. A washer 39 slips over the flange 37 to abut against the under side of the plate 24 and form a good bearing surface for a resilient collar 41 which is snapped over the flange 37. As is shown in Figure 3, the collar 41 is warped so as to apply pressure to both the flat washer 39 and the flange 37. The connector 14 can then move laterally or radially in the plate 24 but cannot move axially with respect thereto.

Since the thickness of the sheet metal forming the plate 24 may not be held to close tolerances, it may be desirable to counterbore a portion shown as the portion 38 in Figure 3 adjacent the opening 42 in which the connector 14 is mounted. By counterboring the portion 38, it is possible to achieve any desired accuracy in the thickness of that portion of the plate 24. This assists the action of the spring 41 since it will not be required to make up for variations in the thickness of the plate 24.

The respective locations of the flanges 36 and 37 may be reversed if desired, in which case the tubular member 34 would be inserted from the opposite or under side of the plate 24 and retained by the washer 39 and spring 41 above the plate. In order to form better electrical conductors all of the parts of the connector 14 and the plates 19, 21 and 24 may be silver plated, if desired.

Modifications of the invention may be apparent to those skilled in the art, without departing from the scope thereof.

What is claimed is:

A socket for a pair of high frequency transmitting tubes, said socket comprising a flat plate having a pair of socket openings adapted to re-

ceive and make mechanical contact with an end portion of said tubes, a pair of flat plate members secured fixedly to said first named plate and parallel therewith with corners overlapping said socket openings, each of said flat plate members having holes therein at said corners, each of said holes having a pin connector mounted therein, each said pin connector being capable of limited radial movement in said holes a first radial flange extending outwardly from each said connector on one side of said plate member to prevent axial movement of said connector through said hole in one direction, a spring collar encircling said connector on the other side of said plate member, and a second radial flange axially spaced on said connector from said first flange, said collar interlocking with said second flange to restrict axial movement of said connector in the other direction, each said connector having a longitudinally slotted portion forming resilient fingers to grip said pins by spring tension.

RUDOLF LEOPOLD.
JOSEPH R. CASAMENTO.
